(57) **CLAIM**

The ornamental design for a window well cover, as shown and described.

DESCRIPTION

FIG. 1 is a top perspective view of window well cover showing my claimed design;

FIG. 2 is an elevational view of the right side thereof with the left side being a mirror image;

FIG. 3 is a top plan view thereof;

FIG. 4 is a front elevational view thereof;

FIG. 5 is a rear elevational view thereof; and

FIG. 6 is a top perspective view of an alternative embodiment of a window well cover showing my claimed design;

FIG. 7 is an elevational view of the right side thereof with the left side being a mirror image;

FIG. 8 is a top plan view thereof;

FIG. 9 is a front elevational view thereof;

FIG. 10 is a rear elevational view thereof; and,

FIG. 11 is top perspective view thereof showing broken-lines to indicate that the window well cover of the present invention can be formed in a range of widths to accommodate different size window wells.

The style of surface shading and degree of transparency or opaqueness forms no part of the claimed invention.
